UNITED STATES PATENT OFFICE

ABRAHAM M. BABITCH, OF FLINT, MICHIGAN, ASSIGNOR TO A C SPARK PLUG COMPANY, OF FLINT, MICHIGAN, A COMPANY OF MICHIGAN

OIL FILTER BY-PASS

Application filed May 9, 1927. Serial No. 189,992.

This invention relates to oil filters as used on automotive vehicles.

It is the object of the invention to construct a by-pass arrangement whereby the oil will be allowed to pass back to the working parts of the engine when the filter becomes clogged or refuses to function. Ordinarily the oil passes from the inlet port through the filter and out at the outlet port but at times the filter becomes clogged and refuses to allow the oil to pass therethrough and in order that the bearing parts of the engine will not suffer for want of oil, or the continuous circulation of the oil interfered with, I provide a means comprising a passage for allowing the oil to travel from the inlet port direct to the outlet port without going through the filter. I make use of a ball valve held on its seat by a coil spring and when the oil pressure becomes sufficiently great, such as will be the case when the filter refuses to function, the ball valve will be lifted off its seat against the pressure of the spring and allow the oil to flow past the valve and through the passage without passing through the filter.

The invention is disclosed in the accompanying drawing in which:

Figure 1 is a view of a filter showing my invention applied thereto, the parts being shown in section.

Figure 2 is a sectional view of line 2—2 of Figure 1.

Referring to Figure 1, 10 designates the filter, 11 the filtering material, 12 the cover, 13 the inlet pipe, and 14 the outlet pipe, while the by-pass arrangement is indicated as a whole at A.

The inlet pipe enters the filter cover at its center and causes the oil to flow through a plug 15 having a central bore or passage 16 in communication with the central passage 17 at substantially the mid portion of the filtering material.

The oil after reaching the passage 17 passes through the filtering material 11 up through the bore or passage 28 in a plug 29 fixed in the filter cover, past the ball valve 30, and into the outlet conduit 27. The purpose of the ball 30 is to prevent the return of

oil from the by-pass passage 20, 26 back to the filter through the bore 28.

By referring to Figure 1, it will be noted that the filtering medium 11 is secured at its center in a groove 40 of the plug 15 by means 55 of a wire 41. At its outer portion the filtering medium is supported by a suitable member 42 which may be a screen or a perforated metal plate. This member 42 is secured to a flange 43 projecting downwardly from the 60 inside of the cover or closure 12. The flange 43 is preferably slightly indented at its outer periphery as shown at 44.

The plug 15 forms a part of the by-pass and is provided with a plurality of radial 65 openings 18 and at the outer terminus of which there is a peripheral groove 19. The plug 15 is inclosed by a cap C threaded thereon and a washer W is used to make a liquid tight joint. The groove 19 is in communication with a conduit 20 normally held closed by a ball valve 21, resting on the seat 22, and held in place by means of a coil spring 23. The coil spring 23 is retained on the ball by means of a plug 24, threaded at 25, into 70 an opening in the by-pass arrangement which is integral with the cover 12. From the conduit 20 a second conduit 26 leads to the outlet passage or conduit 27 the purpose of which is to form a passageway 20, 26 from 75 the groove 19 to the outlet pipe 14, independent of the filter.

A test valve 31, integral with the cover 12, is provided as an auxiliary device to the by-pass arrangement. The purpose of the test 85 valve is to determine whether the filter is functioning. The test valve structure is likewise formed in the cover and is adjacent to and generally parallel to the conduit 27 and comprises a bore 32 extending upwardly 90 through the filter cover 12 and communicating with a conduit 33 at right angles thereto. The test valve has a plug 37, screw threaded as at 34 into the outer end of the conduit 33, and a handle 35 attached to a sleeve 36 screw 95 threaded in the plug 37. The sleeve 36 has a bore as shown at 38, and is provided with openings 39 at its innermost end. In the normal position of the sleeve 36 the holes 39 are closed by the plug 37; however, by turn-

ing the handle 35 the collar may be screwed inwardly, the openings 39 uncovered, and if the filter is working this fact will be evidenced by the flow of oil which will be forced through the opening 39 into the bore or channel 38 to the outside of the test valve. If the filter is clogged or out of commission, no oil will flow out at the outer terminus of the bore 38.

10 The operation of the by-pass arrangement per se is as follows: The oil will enter the inlet pipe 13, pass into the central channel 17, through the filtering material 11, up through the bore 28, past the ball valve 30, into the conduit 27, into the outlet pipe 14. During this operation, the spring 23 is of sufficient strength to hold the ball valve 21 on its seat 22 to prevent any oil from flowing thru the passage 20, 26 to the outlet pipe 14. Should the filter become clogged, then instead of the oil passing to the central passage 17 it will be delivered through the radial openings 18, into the groove 19, conduit 20, past the ball valve 21 (which will be forced 25 from its seat against the tension of the spring 23 by the oil pressure), into the conduit 26, for delivery to conduit 27, and from where it passes into the outlet pipe 14. During this latter operation the ball valve 30 will 30 be pressed against its seat on the plug 29 to prevent the flow of oil to the filter through the bore 28.

I claim:

1. In an oil filter, a closure for one end of 35 said filter, inlet and outlet passages in said closure, a passageway in said closure connecting said inlet and outlet passages, a valve for controlling said passageway, and a plug in said inlet having a plurality of openings and 40 a peripheral groove, to allow the flow of oil to said passageway.

2. In an oil filter, a closure for one end of said filter, inlet and outlet passages in said closure, a passageway in said closure connecting 45 said inlet and outlet passages, a valve for controlling said passageway, and a ported plug in said inlet to allow the flow of oil to said passageway, said filter having a filtering medium secured to said plug.

50 3. In an oil filter, a closure for one end of said filter, inlet and outlet passages in said closure, a passageway in said closure connecting said inlet and outlet passages, a valve for controlling said passageway, means in said 55 inlet to allow the flow of oil to said passageway, a filtering medium secured at its center to said closure, and means remote from the center of said closure for securing said filtering medium at its outer portion to said closure.

4. In an oil filter, a closure for one end of the filter, oil inlet and outlet passages for said filter in said closure, a passageway in said closure between said inlet and outlet passages 65 to at times permit the flow of oil directly

from the inlet to the outlet passages, means to control the oil flow through said passageway, and a test means in said head independent of said passages and passageway to determine the condition of the filter.

In testimony whereof I affix my signature. 70
